MARIE HELENE STEINERT, OF CHEMNITZ, GERMANY

TOOTH-CLEANER

Application filed January 19, 1932, Serial No. 587,466, and in Germany December 31, 1930.

This invention relates to a tooth-cleaner with projecting back.

Tooth-cleaners of various types which do not use bristles but have a projecting back covered with an exchangeable piece of fabric are known already and are chiefly used by persons who have very sensitive gums which are not injured by such cleaners. The latter are quite economical, since they can be used permanently with the exception of the fabric which has to be replaced from time to time, and one of the great difficulties in this respect is to arrange the fabric so that it will be held securely yet interchangeably in position.

It has been proposed to provide the handle of a tooth-cleaner of this class with a small movable tensioning frame corresponding to the extent of the back of the cleaner and capable of being turned over the back and the piece of fabric to hold the latter. However, this method of fastening the fabric suffers from the drawback that the lower and upper portions of the back must have the same width, so that the tensioning frame will project on all sides and interfere with the convenient handling of the cleaner which has to be turned quite often when in use. It would be unavoidable that a cleaner of the kind described touches with its frame the gums or the dental enamel and injures them. Furthermore, according to this method of fastening, the fabric must slightly project beyond the tensioning frame and also interfere with the free and easy use of the cleaner.

According to the invention, these troubles are eliminated by broadening the back of a cleaner upwardly and using its lower narrow portion for holding a cover-like piece of fabric that is narrowed down below.

A tooth-cleaner according to the invention requires no special holding means for the fabric, and its cleaning part has a neat form.

One embodiment of the invention is illustrated in the accompanying drawing.

The fabric portion 3 has the form of a cover and is narrower below, so that it will automatically remain in position after be-

ing placed over the correspondingly shaped back 2 of the cleaner 1, the back 2 being for this purpose broadened in upward direction and thus holds the fabric 3.

It is immaterial whether the back 2 is arranged on a broad or narrow side of the handle of the cleaner 1, but it is advisable to work a rubber ring 4 into the edge of the fabric 3 to secure the latter still more.

Owing to the elimination of special tensioning means for the fabric 3, the device is suited equally well for massaging the gums and cleaning the teeth.

I claim:—

1. A tooth-cleaner of the character described, comprising a handle, a wedge-shaped back forming a part of said handle and projecting from one of the sides thereof, the cleansing surface of said back being flat and wider than the portion of said back adjacent to said handle, and a removable fabric cover surrounding said back, said cover narrowing towards said handle and being held in position by the narrow portion of said back.

2. A tooth-cleaner of the character described, comprising a handle, a wedge-shaped back forming a part of said handle and projecting from one of the sides thereof, the cleansing surface of said back being flat and wider than the portion of said back adjacent to said handle, a removable fabric cover surrounding said back, said cover narrowing towards said handle and being held in position by the narrow portion of said back, and a rubber ring forming a part of said cover, said ring being worked into the edges thereof.

In testimony whereof I have affixed my signature.

MARIE HELENE STEINERT.
